TANNING BOARD

Edwin A. Headland, Beaver, Pa., assignor to Ingram-Richardson Manufacturing Company, Beaver Falls, Pa., a corporation of Pennsylvania

Application January 4, 1936, Serial No. 57,484

3 Claims. (Cl. 149—12)

My invention relates to the stretching and drying of hides and skins, and consists in a new and improved board upon which the hides are pasted before they are passed through the drying chamber. Usually these boards, with the 5 hides pasted to either side thereof are suspended in a vertical position from conveyers which carry the hides through the drying chamber at the proper speed, and the dry hides are stripped off the board after they emerge from the drying 10 chamber.

My invention includes among its objects and 15 advantages: first, lightness, which is important on account of the handling required; second, freedom from breakage or deterioration; third, immunity from chemical action or corrosion; fourth, a surface hard enough and at the same 20 time tough enough to be substantially immune from mechanical abrasion; and fifth, the surface property by reason of which the proper action of the adhesive can be easily obtained and accurately controlled.

I am aware that with respect to any one of 25 these five criteria, fairly satisfactory boards are known in the prior art, but all the prior art plates of which I have knowledge are markedly deficient in one or more of the requirements. For instance, plates according to prior art Patents 1,118,813 and 1,808,306, while not at all 30 unsatisfactory as to the first and third requirements, are materially less effective than plates according to the present invention with respect to the fifth requirement, and hopelessly inferior with respect to the second and fourth requirements because the action of the leather and adhesive loosens the outermost layers or laminations of the plates, and this action necessitates 35 frequent and extensive repairs throughout the life of the plate.

My improved boards are formed of sheets of 40 ferrous metal such as steel, preferably steel which, from its relatively low carbon content, is known as soft steel, and the side surfaces are coated with fused vitreous enamel.

In the accompanying drawing, wherein I illustrate a practical embodiment of the principles of my invention, Fig. 1 is a side elevation of one of my improved drying boards.

Fig. 2 is an enlarged sectional view taken along the line 2—2 in Fig. 1, showing the attachment 50 of the frame to the board.

Fig. 3 is an enlarged fragmentary elevation showing a corner structure.

Fig. 4 is an enlarged fragmentary cross-sectional view of the board.

Referring in detail to the drawing, I represents the board proper which is formed of a steel sheet, preferably soft steel and of the desired thickness, such for instance as one-sixteenth of an inch. The sheets are cut to the 5 proper dimensions.

Each side of the sheet is provided with two or more coats 2 of vitreous enamel, as indicated in Fig. 4, and each coat is separately fused.

Each coat may be applied in the usual manner 10 as by brushing, spraying or dipping, and then fused before the next coat is applied.

The enamel may be of any suitable composition of ceramic, commonly referred to as glass, porcelain, or china when not affixed to metal, 15 and as enamel when affixed to a metal support. The minor variations of composition necessary to secure ceramics best adapted for different types of service are well known in the art, and per se form no part of the present invention. 20

Before the outer coat or coats are fused, it or they are brushed off around the margin of the plate, as indicated at 3 in Fig. 4, so that when the frame 4 is secured in place it engages only the more thinly enameled portions of the plate 25 1 and thus obviates any tendency of the enamel to crack or craze at the junction of the plate 1 with the frame.

To strengthen and stiffen the plate and render it more convenient for handling, and also to 30 prevent contact between the enameled surfaces of adjacent plates or between hides pasted on adjacent plates, I provide suitable frames for the plates, which frames are of greater width than the plate and thus protect the latter. The frame 35 is also of greater width than the combined width of the plate and the hides pasted on both sides of the plate, thus protecting the hides from contact.

The frame may be formed integrally with the 40 sheet as by forming the metal of the sheet to the desired shape before enameling.

However, as the preferable type I have provided a frame formed by bending up sheet steel to form a frame having a hollow box cross-sectional shape with two inwardly extending parallel lips 5 between which the edge of the plate is received, the plate and frame being clamped together by means of the snugly fitting rivets or other members 6 which extend through registering holes in the lips 5 and the plate 1. The lips 5 cover the portions 3 of thinner enamel as indicated in dotted lines in Fig. 4.

At the corners the frame material is mitred as illustrated at 7 in Fig. 3 and said corners are 55

stiffened and reenforced by internal angle plates 8 which are welded or otherwise secured in place to bridge the joints.

In actual practice the use of my improved plates have proved to be attended by greatly improved results. The enameled faces of the plates are permanent and present smooth even surfaces to which the hides may be quickly and conveniently pasted. No wrinkling occurs as the enamel quickly and evenly distributes the heat as the temperature of the plate rises. Again the enamel resists the attack of acids. The plates are strong and durable and are easy and convenient to handle.

In some instances the conveyer is provided with hooks or other means for attaching the plates and thus my plates may be provided with suitable holes, indicated by dotted lines at 9 in Fig. 1 to be engaged by the conveyer members.

Without further elaboration, the foregoing will so fully explain my invention that others may,

by applying knowledge current at the time of application, readily adapt the same for use under various conditions of service.

I claim:—

1. A support for leather drying comprising a 5 thin metal plate, and vitreous enamel fused in multiple layers in equal thicknesses on opposite sides of said plate and presenting the unaltered fused surface of the enamel to the leather.

2. A support for leather drying comprising a 10 thin metal plate, and vitreous enamel fused on both sides of said plate and presenting the unaltered fused surface of the enamel to the leather.

3. A support for leather drying comprising a 15 thin metal plate, and vitreous enamel fused on both sides of said plate and presenting the unaltered fused surface of the enamel to the leather, said unaltered fused enamel surface being smooth and uniform but not plane. 20

EDWIN A. HEADLAND.
